Primary Examiner — Garth Rademaker(74) Attorney, Agent, or Firm — Woodard Emhardt Moriarty McNett & Henry LLP(57) CLAIM

The ornamental design for a spindle vase, as shown and described.

DESCRIPTION

FIG. 1 is a front perspective view of a spindle vase incorporating my new design;

FIG. 2 is a front elevation view thereof, with the rear elevation view being identical thereto;

FIG. 3 is a right side elevation view thereof, with the left side elevation view being identical thereto;

FIG. 4 is an enlarged cross-section view thereof, taken along line 4-4 of FIG. 3, shown in the direction of the arrows;

FIG. 5 is a top plan view thereof; and,

FIG. 6 is a bottom plan view thereof.
